United States Patent Office.

ISAAC STARR, OF PRAIRIEVILLE, MICHIGAN.

Letters Patent No. 86,707, dated February 9, 1869.

IMPROVEMENT IN THRESHING-MACHINES.

The Schedule referred to in these Letters Patent and making part of the same.

To all whom it may concern:

Be it known that I, ISAAC STARR, of Prairievile, in the county of Barry, and State of Michigan, have invented certain new and useful Improvements in Threshing-Machines, and combined mechanism for cleaning, measuring, and sacking grain; and the following is a full, clear, and exact description of the same, reference being had to the accompanying drawings, making a part of this specification, in which—

Figure 1 represents a perspective view or side elevation of the whole machine.

Figure 2 shows a detached view of the receiving, measuring, and discharging-box, for putting the grain into the sacks.

Figure 3 is a side view of the bag or sack-holder, detached.

Figure 4 shows the catch, or holder, for the levers, which hold the sacks.

Figure 5 shows the spring-lever, detached.

Figure 6 shows a section of the grain-elevator, the belt and cups in dotted lines.

Figure 7 represents a detached view of a sieve-frame and hangings.

Figure 8 shows a detached view of the shoe which conducts the grain to the elevator, and the spout for the tailings.

Figure 9 shows a reverse-side elevation of the whole machine.

The object of my invention is to thresh, clean, measure, tally, and sack grain automatically; and

It consists in the arrangement and combination of the grain-elevator, the receiving and measuring-box, the bag or sack-holders, and the tallying-mechanism; also, the construction of the shoe and tailing-board, the frame for holding the sieve, the conducting-board, and mode of operating the same.

To enable others to make and use my invention, I will describe it more in detail, referring to the drawings, and to the letters marked thereon.

I make or use threshing-machines constructed in any of the most approved styles, as seen in figs. 1 and 9, in which I arrange my improved sieve-frame *a a*, and grain-conducting board *A*.

There may be flanges, *a a*, on the sides of the frame, or the grain may be kept from flowing over the edges of the sieve, or screen, *B*, by attaching cloth, or other substance sufficiently flexible to allow the frame to vibrate from side to side, under which screen and frame is placed the shoe or movable board *D*, which serves to conduct the grain to the elevator *E*.

On the upper end of the shoe *D* is the spout *C* to receive the tailings, or refuse grain, and conduct it to the elevator *F*, to run through the machine again.

The screen, or cleaning-apparatus, vibrates between the boards *b b*, made stationary to the frame *G*.

In the ends of the boards *b* is fitted in grooves the tailing-board *d*, so that it can be adjusted up or down, as may be required.

The elevator *E* is so placed in the side of the machine, that it receives the grain from the shoe *D*, and conveys it to the measuring-box *H*, which is constructed with two compartments, *h h*, of equal dimensions.

The bottom of the measuring-box *H* is composed of stiff leather, *I I*, fastened to the centre, as seen in fig. 2.

The box *H* is made to slide on a frame to bring each compartment alternately under the upper end of the grain-elevator *E*, to receive the contents as they are being discharged. When the compartment at one end is filled, the box slides and brings it over the mouth of one of the bags or sacks, *g*, and the weight of the grain depresses and opens the bottom, *I*, and passes through into the sack. At the same time the other compartment is being filled, when the box slides the other way and deposits the grain in the other bag, *g'*, in the same manner; and so alternately the measures are being filled and emptied into bags, while the threshing and cleaning-process is going on.

There may be a tallying and registering-apparatus attached to the machine, and worked by the alternate sliding of the measuring-compartments, so that the number of bushels threshed and sacked up may be known, without keeping count.

The bags, or sacks, *g g'*, are attached to the frame *K* by spring-levers *k k*, which clamp the open ends of the bags on to ledges *j j* on the frame *K*, where they are firmly held, to be filled, by the action of the hooks *i i i i* in the bar *J*, in which the upper or long portion of the levers *k k* is placed.

The main belts, *m n*, of the threshing-machine and separator, are covered by a cap or shield, *M*, to protect them from the sun and weather.

Having thus fully described my invention,

What I claim as new, and desire to secure by Letters Patent, is—

1. The receiving, measuring, and discharging-box, *H*, constructed in the manner herein described.

2. In combination with the box *H*, the elevator *E*, the frame *K*, clamp-levers *k k*, hook-bar *J*, and bags *g g'*, substantially as and for the purposes set forth.

3. The sieve-frame, with its flanges *a a*, or cloth-attachments, to prevent the overflow at the sides, when connected with the shoe *D*, spout *C*, and tailing-board *D*, as and for the purposes herein specified.

ISAAC STARR.
